LOOP ANTENNA

Filed June 4, 1923

Patented Apr. 16, 1929.

1,709,666

UNITED STATES PATENT OFFICE.

PAUL M. HENGSTENBERG, OF WILKINSBURG, PENNSYLVANIA, ASSIGNOR TO WESTINGHOUSE ELECTRIC & MANUFACTURING COMPANY, A CORPORATION OF PENNSYLVANIA.

LOOP ANTENNA.

Application filed June 4, 1923. Serial No. 643,170.

My invention relates to antennæ and particularly to the construction of loop antennæ for radio signalling.

The object of my invention is to provide a 5 loop antenna of simple, convenient construction and of suitable size for efficient operation in connection with radio signalling systems, and which shall also be conveniently foldable into a compact form.

10 In carrying my invention into effect, I construct a loop antennæ consisting of a plurality of radial arms carrying a plurality of turns of wire. The radial arms are supported by a hub to which they are hinged 15 and in which they are held in position by a clamping plate. The antennæ as a whole is then supported in an upright position by a "crow-foot" stand, attached to the downwardly extending radial arm.

20 Other objects and structural details of my invention will be apparent from the following description and claims when read in connection with the accompanying drawing, wherein

25 Fig. 1 is a view in elevation of my device.

Fig. 2 is an enlarged view of the hubs and inner ends of the radial arms of my invention, a portion of the clamping plate being broken away.

30 Fig. 3 is an edge view of the hub shown in Fig. 2 from a position at right angles to that of Fig. 2.

Fig. 4 is a side view of the "crow-foot" stand shown in Fig. 1.

35 Fig. 5 is a view of my antenna as it appears when folded.

Fig. 6 is an enlarged view of the hub and clamping plate, showing the manner in which the arms are loosely supported thereby.

40 In all of the figures, the like reference characters refer to corresponding parts.

In the drawing, the recessed hub plate 1 and the notched clamping plate 2 form supporting, separating, and clamping elements 45 which hold in position a number of radial arms 3. The outer extremities of the arms 3 support a series of turns of wire 4. These turns of wire may be held in place by being passed through holes drilled in the outer ends of arms 3 or by any equivalent mechanical clamping device. The respective ends of the wire forming the turns 4 are attached to binding posts 5 and 6, which may be upon

the same or upon different radial arms, according to the use to which the loop is to be put. One of the radial arms 3 is made longer than the others, forming an extension 7. This extension is a part of the crow-foot stand which is shown in side view in Fig. 4. 60

The base of this stand consists of bars 8, 9 and 11 which are rotatably attached to a pair of bearing plates 15 and 16 in which they are held in position by friction fit. A spacer bar 17 attached between the outer end 65 of bar 11 and a point on extension 7 maintains a condition of perpendicularity between extension 7 and the foot structure 8, 9, 11, 15 and 16.

When extended into the operative position illustrated in Figs. 1 and 4, the bars 8, 9 and 11 diverge radially, the angle subtended by any two of the bars being one hundred and twenty degrees. In the folded position, the bars 8 and 9 lie against and in 70 contact with the bar 11, on opposite sides thereof, the bar 11 being folded up in contact with support 7 as illustrated in Fig. 5.

The hub element, shown on a larger scale in Figs. 2, 3 and 6, comprises a recessed plate 80 1, having a central boss 20 through which passes a clamping bolt 12. The head 21 of the clamping bolt 12 fits into a counter-sunk opening in a clamping plate 2, provided with irregularly shaped notches 18. The plate 85 1 is provided with a plurality of radially cut channels 22, of sufficient width to accommodate the ends of the arms 3 when the loop is extended in operative position, such ends then projecting into a circular recess 90 23 between the outer rim of the plate 1 and the central boss 20. Each of the arms 3 is provided with an opening 24 through its inner end, and a continuous ring 25 passes through all of these openings, the arms being 95 strung on the ring 25 in the same manner that keys are strung on the ordinary and well known key ring. The ring 25 has no connection with either the plate 1, or the clamping plate 2, and it and the arms 3 may 100 be entirely disassociated from the two plates by removing the wing-nut 14 and the clamping bolt 12.

As illustrated in Figs. 1 and 3, in the extended position, the arms 3 fit into the radial channels 22 of the plate 1, being prevented from radial movement by the ring, and being prevented from collapsing into the folded

position by pressure of the clamping plate 2.

- When it is desired to fold the loop for transporting, the wing nut 14 is loosened, permitting the plates 1 and 2 to separate somewhat, and to rotate with reference to each other. The plate 2 is then rotated sufficiently to bring the notches 18 opposite the ends of the arms 3, permitting the arms to drop into the position illustrated in Fig. 5.
- 10 The plate 2 is thereafter rotated enough to cause the inner ends of the arms to move into the enlarged portions of the openings 18, and the plate 1 is also rotated enough to position the un-channelled portions thereof above the said ends. The relative position of the plates 1, 2, the ring, and the inner ends of the arms, immediately previous to the locking operation, is shown clearly in Fig. 6.
- 15 To lock the loop in the folded position, it is merely necessary to tighten the wing-nut 14, thus drawing the plates 1 and 2 toward each other, and, since the arms 3 are prevented from moving downward by the engagement of the ring 25 with the locking plate 2, consequently clamping the ends against motion.

While I have shown only one embodiment of my invention in the accompanying drawing, it is capable of other changes and modifications without departing from the spirit and scope of my invention and I desire, therefore, that only such limitations shall be placed thereon as are indicated in the prior art or in the appended claims.

I claim as my invention:

1. A folding-loop antenna comprising a hub device including a circular disc member having a central recess and radial grooves, 40 a circular clamping plate coplanar therewith and having radial slots widened at the inner ends, and a clamping bolt through the respective axes thereof, a plurality of radial arms hinged within said grooves, and a plu-

rality of turns of conductor wire supported 45 on said arms.

2. A folding loop antenna, comprising a plurality of turns of wire, a plurality of radial arms, a plurality of attachments at the outer extremities of said arms for holding said turns of wire, a plate having recesses in which said radial arms are journaled, a notched clamping plate for holding said arms in said recesses, a bolt extending axially through said plates and serving to 50 hold them in operative relation and a crow-foot stand attached to the outer end of one of said arms.

3. A folding-loop antenna comprising a hub device including a circular disc member 60 having a central recess and radial grooves, a circular clamping plate co-planar therewith and having radial slots widened at the inner ends and a clamping bolt through the respective axes thereof, a plurality of radial arms 65 hinged within said grooves and a plurality of turns of conductor wire supported on said arms, said plate being adapted to rotate on said bolt, and means whereby said arms are locked into an extended position or may be 70 folded or locked in a folded position.

4. A foldable support for loop-antennæ, comprising a plurality of arms, unitary means extending through one end of each of said arms, a hub member comprising a plurality of radially recessed discs held in parallel relation by a clamping device extending through said unitary means, and means for controlling said clamping device, the recesses in said discs being so arranged that said 75 arms may be extended and clamped in a plane parallel to said discs or may be folded and clamped perpendicularly to said discs.

In testimony whereof, I have hereunto subscribed my name this 21st day of May, 85 1923.

PAUL M. HENGSTENBERG.
